UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP CONSISTING OF FRANCIS E. MYERS AND PHILIP A. MYERS.

SELF-OILING POWER-PUMP.

1,385,144.

Specification of Letters Patent. Patented July 19, 1921.

Application filed November 13, 1919. Serial No. 337,644.

To all whom it may concern:

Be it known that I, PHILIP A. MYERS, a citizen of the United States, residing at Ashland, in the county of Ashland and State of Ohio, have invented certain new and useful Improvements in Self-Oiling Power-Pumps, of which the following is a specification, reference being had therein to the accompanying drawing.

10 This invention relates to self-oiling power pumps, and has for its particular object to provide an improved self-oiling system for power pumps of the general type disclosed in my copending application for Letters

15 Patent Serial #185,248, filed August 9, 1917.

A particular object of the invention is to provide self-oiling means for the pitman and piston head bearing, or rather to provide a modified construction of the power head casing as distinguished from the casing construction shown in my copending application above referred to, whereby the self-oiling of the pitman and piston head bearing will be effected by the standard operable 25 parts of the power head.

A further object of the present invention is to provide a further modification of the power head casing construction relative to the stuffing box interposed between the power 30 head casing and the pump cylinder, whereby water accumulating from seepage through the stuffing box will not flow into the power head casing and affect the oil therein.

35 While the invention is in the nature of refinements and of simple mechanical forms that do not add materially to manufacturing costs, it adds nevertheless materially to the efficiency of operation of the power head as, 40 obviously, a mixture of water with the oil will depreciate the lubricating qualities of the oil, and insufficient lubrication of any of the operable parts, as of the pitman and piston head bearing, will affect adversely the 45 operation of the power head as a whole, both conditions being corrected by the present invention.

In the accompanying drawings:—

Figure 1 is a longitudinal sectional view 50 of a power head having the improved self-oiling and water drain applied thereto, and

Fig. 2 is a cross-sectional view taken on the line 2—2 of Fig. 1.

The construction here shown consists of the integral power head casing 1 having 55 base portions 2 and 3, and a cover 4 whereby convenient access to the interior of the casing is provided. A guide cylinder 5 is also preferably formed integrally with the casing and serves as a support and guide for 60 the piston head 6. The crank shaft 7 is mounted in suitable bearings (not shown) secured in the opposite sides of the casing 1, and the crank arm or pitman is connected to the crank shaft by the usual construction 65 consisting of the eccentric disk 8 and the co-operating band or collar 9 of the pitman. The opposite end 10 of the pitman is connected to the piston head 6 in the usual manner by means of a transverse bearing shaft 70 11, an oil aperture 13 being formed in the end of the pitman and another oil aperture 12 opposite the same in the piston head whereby oil will be admitted to the bearing 11.

75 The power head may be operated from any suitable source of power by effecting operable connections with the drive shaft 14 which has secured thereto internally of the casing 1, a pinion 15 meshing with a gear 16 80 secured to the crank shaft. The crank casing is normally supplied with oil of sufficient quantity or required depth to cause a portion of the gear 16 and the lower portion of the disk 8 and collar 9 to be immersed 85 therein, thus with the operation of the power head portions of the oil will be splashed upwardly against the upper wall of the casing over the pinion 15 and into the space 17 above the shelf 18 which is disposed transversely of the casing 1 and serves to drain through a discharge aperture 19 portions of the oil into the oil apertures 12 and 13 and to the bearing 11.

90 Thus, with the operation of the power head, all portions of the operable parts within the crank casing will be constantly self oiled, the oil flowing through the aperture 12, serving also to oil more thoroughly the working surface of the piston guide head 6, 100 a portion of the surface being exposed as it travels beneath the discharge aperture 19, and thus coming in contact with the oil flowing from the shelf 18. The excess oil flowing from the piston head and bearing 11 is returned to the pump or oil reservoir in the 105

casing by gravity flow, as will be obvious from the construction shown of the casing.

5 A pump 20, which may be of any suitable construction, is mounted, as here shown, relative to the power head with the pump cylinder 21 and piston or plunger 22 in alinement with the piston head 6 and guide cylinder 5, a piston rod 23 connecting the piston to the piston head in the usual form 10 of construction.

15 As here shown, a cylinder head 24 is employed to serve the double purpose of a closure for both the power head and pump casing, the cylinder head being of novel construction whereby a plurality of pumps may be mounted interchangeably on a single power head as set forth in a copending application for letters Patent.

20 The cylinder head 24 also is provided with suitable means to form part of a stuffing box 25, other parts of the stuffing box, 26, 27 and 28, being secured to or supported by the head 24, the details of construction and arrangement not being claimed as a part of the 25 present invention.

25 The opposite sides of the casing 1 are open to the atmosphere, as shown at 29, and the member 27 of the stuffing box, as here shown, is provided with air apertures 30, which 30 relieve the pressure about the piston rod at this point and tend to prevent the seepage of water from the pump casing through the outer member 28 of the stuffing box. The stuffing box packing 31 acts further to prevent 35 seepage of water along the piston rod.

35 It has been found practically impossible in the operation of power pumps of this character to effectually prevent seepage of more or less water along the piston rod, notwithstanding the use of the most effective 40 forms of stuffing box construction. Under the most favorable conditions, the seepage is of sufficient extent that the water, if permitted to be drained into the gear casing of 45 the power head, will in a short time render ineffective the lubricating qualities of the oil therein.

45 Means are provided in the present invention therefore to cause the water to drain 50 from the stuffing box and the piston rod into a water receptacle 32 adjacent the gear casing, from which the water may be discharged through a drain 33, and thus be prevented from flowing into the crank casing.

55 While the improvements of the power head casing comprised in the present invention add but very little, if any, to manufacturing costs, both the self-oiling feature of the piston head and piston head bearing and 60 the water drain from the stuffing box being made as here shown, integrally with the main casing, the effect of the improvements on the operation of the power head is of material consequence with respect to both the 65 efficiency and economy of operation.

In event that the drain 33 should become clogged and the water pan 32 filled with water, the inner wall 34 thereof, being higher than the side walls 35, will cause the water to overflow the sides 35 of the water pan, thus preventing any portion of the water 70 entering the gear casing.

Having thus fully described my invention, what I claim as new and desire to secure by Letters Patent, is:

75 1. In a power head the combination with a gear casing adapted to contain a supply of oil, of a gear drive, a crank shaft and pitman connections mounted in said casing, comprising a pitman head, a piston head bearing and pitman crank bearing in the piston head, an oil aperture in the piston head bearing, an oil aperture arranged relative thereto in the end of the pitman, an oil aperture in the casing and an oil guide leading thereto, whereby upon the operation of the power head mechanism parts thereof will contact with the oil and cause portions of the latter to be conveyed by the guide to and through the casing to the piston head and 80 piston head bearing and to and through the pitman to the crank bearing.

85 2. In a power head, the combination with a gear casing adapted to contain a supply of oil, a pump adapted to be arranged in operative relation to said power head, a stuffing box interposed between said pump and the gear casing and a piston rod operating through said stuffing box, of a receptacle for liquid arranged adjacent the stuffing box 90 and between the pump and the gear casing, and means to conduct liquid escaping through the stuffing box from the pump casing into said receptacle one of whose walls is lower than the wall dividing it from the 95 gear casing whereby the liquid may automatically escape and overflow into the gear casing is prevented.

100 3. In a power head, the combination with a gear casing adapted to contain a supply of oil, a pump adapted to be arranged in operative relation to said power head, a stuffing box interposed between said pump and the gear casing and a piston rod operating through said stuffing box, of a receptacle for liquid arranged adjacent the stuffing box and between the pump and the gear casing, and means to conduct liquid escaping through the stuffing box from the pump casing into 105 said receptacle, one of whose walls is lower than the wall dividing it from the gear casing whereby the liquid may automatically escape and overflow into the gear casing is prevented.

110 4. In a power head, the combination with a gear casing adapted to contain a supply of oil, a pump adapted to be arranged in operative relation to said power head, a stuffing box interposed between said pump and the gear casing and a piston rod operating 115

through said stuffing box, of a receptacle for liquid disposed transversely of the gear casing adjacent the stuffing box, between the pump and gear casing and having a drain 5 aperture to discharge liquid therefrom, and means to conduct liquid escaping through the stuffing box from the pump casing into

said receptacle, one of whose walls is lower than the wall dividing it from the gear casing whereby the liquid may automatically 10 escape and overflow into the gear casing is prevented.

In testimony whereof I affix my signature.
PHILIP A. MYERS.
